REFRIGERATOR CAR CONSTRUCTION

John S. Lundvall, Chicago, Ill., assignor to Union
Asbestos & Rubber Company, Chicago, Ill., a
corporation of Illinois

Application October 2, 1936, Serial No. 103,735

4 Claims. (Cl. 105—423)

The present invention relates to refrigerator car construction, and is particularly concerned with an improved wall construction for steel refrigerator cars.

One of the objects of the invention is the provision of an improved mode of attachment of the car insulation and nailing strips to the walls of steel refrigerator cars by means of which the weight of the car may be reduced and a greater insulating efficiency achieved at a lower cost.

Another object is the provision of an improved construction including an insulated squeeze strip which is also adapted to be used as a nailing strip and which is used to attach the insulation to the wall of a steel car.

Another object is the provision of an improved construction including a squeeze strip bearing washer which is adapted to house the nut and end of the securing bolts and which is adapted to prevent splitting of the squeeze strip or nailing strip and to secure the wooden strip in such manner that it is adapted to be used both as a nailing strip and for securing the insulation in place.

Other objects and advantages of the invention will be apparent from the following description and the accompanying drawing, in which similar characters of reference indicate similar parts throughout the several views.

Referring to the single sheet of drawings accompanying this specification,

Fig. 1 is a fragmentary, horizontal sectional view, taken through a portion of the wall of a refrigerator car constructed according to the present invention, the section being taken in a plane at right angles to the vertical wall;

Fig. 2 is a fragmentary elevational view of the bearing washer and nailing strip of Fig. 1, taken from the bottom of Fig. 1, with the sheathing removed;

Fig. 3 is a view in perspective of the bearing washer employed in Figs. 1 and 2;

Fig. 4 is a view similar to Fig. 1 of a modification in which the securing bolts are mounted upon a different form of structural steel member, and in which a different form of insulation is employed.

Referring to Fig. 1, 10 indicates in its entirety the refrigerator car wall, which may comprise a plurality of sheets of steel 11, 12, which form the external covering for the car wall. These sheets may be suitably joined together by rivets 13 or by welding, any of the modern forms of which may be employed.

The rivets 13 may also be used to secure in place one of the parallel flanges 14 of a Z bar 15,

which has its other parallel flange 16 spaced from the steel sheets 11, 12. Z bars 15 preferably extend from the bottom to the top of the car, and are located at regularly spaced intervals, with sufficient proximity between them to provide suitable support for the insulation and for nailing strips used to support the sheathing or wood lining 17.

The flanges 16 of the Z bars may be provided with apertures 18 for receiving the shanks 19 of screw bolts. The screw bolts preferably have their heads 20 engaging the outer surface of the flanges 16 and the heads 20 are preferably welded in place, as, for example, by the welds 21 at the edge of the head. Thus the Z bars 15 are each provided with a plurality of spaced, inwardly projecting and fixedly secured threaded members 19 for supporting insulation and nailing strips.

The insulation may consist of various suitable forms, such as the stiff insulation board 22 and/or the flexible bats 23 of sheet insulation, such as felt made of suitable vegetable, animal, or mineral fibers, preferably the former, on account of economy.

The bolts 19 project through the apertures 24 in the layers of insulation, and are adapted to project through the bores 25, suitably located in the squeeze strip 26.

The squeeze strip 26 may consist of a wooden strip of suitable size to be used for a nailing strip 30 and substantially rectangular in cross section, except that the two inner corners 27 have been rounded off to conform to the shape of the clamped layers of insulation.

The bearing washers 28 are preferably used on each of the bolts 19 for distributing the pressure over the area of the strip 26, preventing splitting of the strip, and for housing the nut 29. A bearing washer is shown in perspective in Fig. 3. It comprises a stamped sheet metal member 40 provided with a flat body portion 30, which may be substantially rectangular in plan.

The body portion 30 is provided at a centrally located point with the aperture 31 for passing the bolt 19, and with a substantially cylindrical cup-shaped stamped formation 32 arranged concentrically with respect to the aperture 31 and of sufficient depth to receive the nut 29 and the end of the bolt 19; that is, when the insulation layers 22, 23 are sufficiently compressed to secure them in place, the bolt 19 does not project beyond the outer face of the body 30 of the bearing washer 28. The cup-shaped formation 32 is also of sufficient diameter so that the nut 29 may turn within the depression of the cup.

The body portion 38 is preferably provided with a pair of confining flanges 33, 34, one located on each side of the strip 26 and closely engaging the sides 35 of the strip 26.

5 The front face 36 of the strip 26 is provided with a plurality of enlarged bores or counterbores concentrically located with respect to the bores 25 for receiving the stamped formations 32 of the bearing washers 28.

10 In some embodiments of the invention the squeeze strips 26 may also be cut in from the point 37 to the point 38 sufficiently to receive the body 38 of the bearing washer so that the outer face 36 of the bearing washer is flush with the surface 36 of the squeeze strips 26, if desired.

15 The bearing washers 28 leave the major portion of the squeeze strips 26 exposed to be used as a nailing strip, and thus the inner wooden lining or sheathing 17 of the car may be nailed 20 to the strips 26.

25 The wooden lining 17 and the external steel sheets 11, 12 provide a housing for the insulation 22, 23, and are adapted to maintain it in dry and efficient condition. The steel sheets 11, 12 are preferably coated on the inside with a layer 11' of asphaltum and, if desired, water-proofing may also be employed between the nailing strips and the lining 17.

30 Referring to Fig. 4, this is a modification in which the structural steel member 40 is of substantially U shape, the bolt 19 being secured to the web 41, which is carried by a pair of side flanges 42, 43 and secured to the steel plate 11 by foot flanges 44, 45 and suitable rivets or 35 welding.

35 The bearing washers 28 are adapted to provide a depression for housing the nut 29 and end of bolt 19 so that these members may cup below the surface of the squeeze strip 26, and the bearing washers also confine the squeeze strip at its lateral edges so that splitting of the strip is prevented.

40 The squeeze strips are adapted to secure the layers of insulation to the bolts 19, which are secured to the car wall in such manner that the insulation is spaced from the car wall and adapted to be held in proper position so that it will have the greatest heat insulating value.

45 The present refrigerator car construction is light and strong, yet the wall has a high insulation value and is adapted to perform its functions very efficiently.

50 While I have illustrated a preferred embodiment of my invention, many modifications may be made without departing from the spirit of the invention, and I do not wish to be limited to the precise details of construction set forth, but desire to avail myself of all changes within the scope of the appended claims.

55 Having thus described my invention, what I claim as new and desire to secure by Letters Patent of the United States, is:

60 1. In a refrigerator car, the combination of a sheet metal exterior wall with a structural frame member having a pair of attaching flanges extending substantially parallel to said exterior wall, one of said attaching flanges being secured to said exterior wall, and the other being located in spaced relation thereto, said latter attaching 65 flange being provided with a plurality of apertures, securing members located in said apertures and projecting into said car, refrigerator car insulating material having perforations for said securing members and mounted on said securing 70 members in engagement with said latter attach-

ing flange, a squeeze strip of lumber engaging said insulation and clamping it between said squeeze strip and said latter attaching flange, said squeeze strip being provided with a plurality of apertures registering with the apertures in said latter attaching flange and having sockets surrounding the securing members on the inside of the car, and a cup-shaped metallic member having an aperture for receiving a securing member, and having a socket to seat in a socket of said squeeze strip and for receiving a threaded member on said securing member, said cup-shaped member having laterally extending and outwardly extending flanges embracing the inner portion of said squeeze strip and the inner corner portions of said squeeze strip whereby splitting is prevented and the wooden strip is reinforced. 15

2. In a refrigerator car, the combination of a sheet metal exterior wall with a structural frame member having a pair of attaching flanges extending substantially parallel to said exterior wall, one of said attaching flanges being secured to said exterior wall, and the other being located in spaced relation thereto, said latter attaching flange being provided with a plurality of apertures, securing members located in said apertures and projecting into said car, refrigerator car insulating material having perforations for said securing members and mounted on said securing members in engagement with said latter attaching flange, a squeeze strip of lumber engaging said insulation and clamping it between said squeeze strip and said latter attaching flange, said squeeze strip being provided with a plurality of apertures registering with the apertures in said latter attaching flange and having sockets surrounding the securing members on the inside of the car, and a cup-shaped metallic member having an aperture for receiving a securing member, and having a socket for receiving a threaded member on said securing means, said cup-shaped member having laterally extending and outwardly extending flanges embracing the inner portion of said squeeze strip and the inner corner portions of said squeeze strip whereby splitting is prevented and the wooden strip is reinforced, and a layer of sheathing carried by said squeeze strip, said strip acting as a nailing strip. 45

3. In a refrigerator car, the combination of a sheet metal exterior wall with a structural frame member having a pair of attaching flanges extending substantially parallel to said exterior wall, one of said attaching flanges being secured to said exterior wall, and the other being located in spaced relation thereto, said latter attaching flange being provided with a plurality of apertures, securing members located in said apertures and projecting into said car, refrigerator car insulating material having perforations for said securing members and mounted on said securing members in engagement with said latter attaching flange, a squeeze strip of lumber mounted on said securing members and engaging said insulation and clamping it between said squeeze strip and said latter attaching flange, said squeeze strip being provided with a plurality of apertures registering with the apertures in said latter attaching flange and having sockets surrounding the securing members on the inside of the car, and a cup-shaped metallic member having an aperture for receiving a securing member, and having a socket to seat in a socket of said squeeze strip and for receiving a threaded member on said securing means, said cup-shaped member having laterally extending and thence 75

outwardly extending flanges embracing the inner portion of said squeeze strip and the inner corner portions of said squeeze strip whereby splitting is prevented and the wooden strip is reinforced, 5 said structural member comprising a Z-shaped metal bar, and said securing members comprising bolts welded to one of the flanges of said bar.

4. In a refrigerator car, the combination of a sheet metal exterior wall with a structural frame member having a pair of attaching flanges extending substantially parallel to said exterior wall, one of said attaching flanges being secured to said exterior wall, and the other being located in spaced relation thereto, said latter attaching flange being provided with a plurality of apertures, securing members located in said apertures and projecting into said car, refrigerator car insulating material having perforations for said securing member and mounted on said securing member in engagement with said latter attaching flange, a squeeze strip of lumber engaging said insulation and clamping it between

said squeeze strip and said latter attaching flange, said squeeze strip being provided with a plurality of apertures registering with the apertures in said latter attaching flange and having sockets surrounding the securing members on the inside of the car, and a cup-shaped metallic member having an aperture for receiving a securing member, and having a socket to seat in a socket of said squeeze strip and for receiving a threaded member on said securing means, said cup-shaped member having laterally extending and outwardly extending flanges embracing the inner portion of said squeeze strip and the inner corner portions of said squeeze strip whereby splitting is prevented and the wooden strip is reinforced, said structural member comprising a channeled member provided with laterally projecting flanges, and said securing means comprising a plurality of bolts welded to the yoke of said channeled member. 5 10 15 20
